UNITED STATES PATENT OFFICE.

RICHARD L. NEUBERT, OF KNOXVILLE, TENNESSEE.

TRAVELING HOIST.

1,389,265.

Specification of Letters Patent. Patented Aug. 30, 1921.

Application filed December 20, 1919. Serial No. 346,258.

To all whom it may concern:

Be it known that I, RICHARD L. NEUBERT, a citizen of the United States, residing at Knoxville, in the county of Knox and State 5 of Tennessee, have invented a new and useful Improvement in Traveling Hoists, of which the following is a specification, reference being had to the accompanying drawing.

10 My improvement relates particularly to hoisting and carrying mechanism wherein a cable or wire rope or similar member forms an elevated track on which is supported a depending carriage which is made to travel 15 on said track by means of ropes or cables leading to a station at or in the direction of one end of said track and being there connected with drums or windlasses, a cable or rope depending from the carriage and serving as a "load-line" or "picking-up line" 20 which is raised and lowered to handle the loads which the apparatus is to transport.

One object of the invention is to provide such an apparatus adapted to raise and 25 transport heavy loads over a relatively extended range, both longitudinal and lateral. For example, the apparatus is intended to collect saw-logs scattered over an extended land surface and deliver them on railway 30 cars or elsewhere. For this service, an extremely strong equipment is required; but strength must be attained with the least possible weight of the traveling part of the equipment, because said part of the equipment 35 is usually supported by a long cable which is supported only at its ends. A further object of the invention is to so control ropes or cables as to prevent their twisting and over-lapping and consequent kinking 40 and entangling.

In the accompanying drawings,

Figure 1 is a side elevation illustrating an apparatus embodying my improvement, a part of the figure being in diagram;

45 Fig. 2 is an elevation on a larger scale illustrating the left hand carriage, shown in Fig. 1;

Fig. 3 is a plan of the carriage shown in Fig. 2;

50 Fig. 4 is a horizontal section on the line 4-4, of Fig. 2;

Fig. 5 is an elevation of said carriage, looking toward the right as shown in Fig. 2;

Fig. 6 is a section on the line, 6-6, of Fig. 2, looking toward the right; 55

Fig. 7 is a horizontal section on the line, 7-7, of Fig. 2;

Fig. 8 is a horizontal section on the line, 8-8, of Fig. 2;

Fig. 9 is an elevation on a larger scale of 60 the right hand carriage shown in Fig. 1;

Fig. 10 is a plan of the carriage shown by Fig. 9;

Fig. 11 is an elevation of said carriage, looking toward the right as shown in Fig. 9; 65

Fig. 12 is a horizontal section on the line, 12-12, of Fig. 9;

Fig. 13 is an upright section on the line, 13-13, of Fig. 9, looking toward the right;

Fig. 14 is a section on the line 14-14, of 70 Fig. 9, looking toward the right;

Fig. 15 is a horizontal section on the line, 15-15, of Fig. 9;

Fig. 16 is a horizontal section on the line, 16-16, of Fig. 9. 75

Referring to said drawings, A is the elevated track upon which the two carriages, B and C, travel. Said track is usually a horizontal cable secured by its ends to fixed objects at suitable elevations. 80

The carriage, B, has two grooved wheels or rollers, B¹. Each of said wheels loosely surrounds a spacing tube, B³. A bolt, B², extends through the spacing tube. At each side of the pair of wheels is a horizontal 85 channel bar, B⁴, which is penetrated by one of the bolts, B². At each side of the left hand wheel, as viewed in the drawings, a bar, B⁵, is located between the wheel and the channel bar, B⁴. The adjacent bolt, B², also 90 penetrates the bars, B⁵. Bars, B⁶, are similarly applied between the right hand wheel, B¹, and the bars, B⁴, and are similarly penetrated by the bolt, B², and a spacing tube, B³, surrounds said bolt. The lower ends of 95 the bars, B⁵ and B⁶, over-lap each other and are penetrated by a horizontal bolt, B⁷, the forward bar, B⁵, over-lapping the forward bar, B⁶, and said bars forming a pair, and the rear bar, B⁵, over-lapping the rear bar, B⁶, and said bars forming a pair.

A clevis, B⁸, is also applied to the bolt, B⁷, one eye of the clevis being at the outer side of each pair of the overlapping bars, B⁵ and B⁶. Said clevis is directed toward the left. 105 The eye, B⁹, of a swivel block, B¹⁰, rests be-

- tween the pairs of bars, B^5 and B^6 , and is penetrated by the bolt, B^7 . Thus said bolt is made to support said block. At the front and at the rear of the carriage an upright bar, B^{11} , is suitably secured to the adjacent horizontal channel bar, B^4 , and the oblique bars, B^5 and B^6 . Two grooved rollers, B^{12} , are placed one above the other between said bars and supported on horizontal bolts, B^{13} .
- 10 The function of said rollers is to support and guide the cable, G , as will be described farther on. The function of the swivel block, B^{10} , is to support and guide the load-line, H , to be described farther on. The 15 function of the carriage, B , is to support and carry the rollers, B^{12} , and the swivel block, B^{10} .

A clevis, B^{14} , is coupled to the diagonal bars, B^6 , by means of a horizontal bolt, B^{15} , 20 extending through the clevis and said bars.

A buffer block, B^{16} , is placed between the right hand ends of the channel bars, B^4 , and is secured in position by the horizontal bolt, B^{17} , extending through said bars and said 25 block.

Immediately below each roller, B^1 , a roller, B^{18} , is placed between the diagonal bars, B^5 and B^6 , and is there supported by a transverse bolt, B^{19} . For convenience, the 30 carriage, B , will be termed the "load carriage."

In the carriage, C , the wheels, C^1 , the channel bars, C^4 , the bolts, C^2 , the spacing tubes, C^3 , the diagonal bars, C^5 and C^6 , and 35 the bolt, C^7 , correspond, respectively, to the parts, B^1 to B^7 , inclusive, in the carriage, B .

Below and parallel to each channel bar, C^4 , a channel bar, C^8 , extends from the adjacent bar, C^5 , to the adjacent bar, C^6 , and has 40 its ends suitably secured to said bars. At the front and at the rear an upright bar, C^9 , has its lower end forked and suitably secured to the adjacent bars, C^5 and C^6 , and extends upward along the inner face of the adjacent bar, C^8 . A grooved roller, C^{10} , is 45 located between the bars, C^9 , opposite the bars, C^8 . A horizontal bolt, C^{12} , penetrates the bars, C^8 and C^9 , and the roller, C^{10} , and a spacing tube, C^{11} , located within the wheel.

50 Above said roller, a bolt, C^{13} , extends horizontally through the two bars, C^9 , and is surrounded by a loose tube, C^{14} .

A clamping block, C^{15} , is placed between the lower ends of the pairs of diagonal bars, C^5 and C^6 . Screw bolts, C^7 , extend horizontally 55 through the over-lapping ends of each pair of diagonal bars into the clamping block. Thus the clamping block is supported to permit rocking on the journals formed by the screw bolts. In the upper face of and parallel to the length of the clamping block is a channel, C^{17} . Said channel is of proper width and depth to allow the load-line, H , to lie therein with its

axial line approximately cutting the axial 65 line of the screw bolts, C^{16} . Two U -bolts, C^{18} , extend across the load-line, H , and have their arms extending downward through the clamping block. Said U -bolts firmly clamp the load-line into the groove, C^{17} . When 70 the nuts on the U -bolts have been loosened, the load-line may be shifted endwise in the clamping block.

A buffer block, C^{20} , similar to the buffer block, B^{15} , is similarly applied to the left 75 hand ends of the channel bars, C^4 , of the carriage, C , by means of a bolt, C^{21} . Said buffers are intended to meet and receive shock when the carriages are accidentally brought together.

A roller, C^{22} , similar to the rollers, B^{17} , of the carriage, B , is placed below each wheel, C^1 , and between the bars, C^5 and C^6 , and supported by bolts, C^{23} , extending through the bars and rollers. For convenience, the carriage, C , is termed the clamp carriage.

The drums, G^1 , F^1 , and H^2 , shown in diagram on the drawings, are conveniently located, in the well-known manner, for controlling the different cables or lines forming 90 a part of the apparatus.

The load-line, H , extends upward along the left of the swivel-block, B^{10} , and then rightward over said block and through the 95 clamping block and then over guide rollers, H^1 , to the load line drum, H^2 . A load carriage cable, F , extends from the clevis, B^8 , to the load carriage line drum, F^1 . A clamp carriage cable, G , extends from the clevis, B^{14} , rightward to and around the roller, C^{10} , 100 and thence leftward between the rollers, B^{12} , of the carriage, B , and thence to the clamp carriage line drum, G^1 .

The operation is as follows: 105

Let it be assumed that the carriages are on the track, A , at any desired distance rightward of the drums and that the carriages are separated to bring the free end of the load line above the ground, and that said end of the line is to be lowered to receive a load either directly under the track or a short distance or several hundred feet side- 110 wise from the track.

To lower the free end of the load-line into 115 position to receive the load, the carriages are drawn toward each other by winding the cable, G , on the drum, G^1 , and allowing the cable, F , to unwind from the drum, F^1 , the drum, H^2 , being held stationary. Thus the 120 carriage, B , is moved toward the carriage, C , and during such movement the load-line passes leftward through the swivel-block, B^{10} .

When the load has been attached to the 125 load-line, H , the carriages are to be separated until the load-line, H , has been drawn rightward through the swivel-block far

enough to lift the load to the desired height. Then the two carriages are to be held at the same distance from each other and moved simultaneously to the left along the track, 5 A, until the point for discharge of the load has been reached. The separation and simultaneous movement of the carriages are effected by causing the drum, H², to wind the load-line and at the same time allowing 10 the drums, F¹ and G¹, to unwind, brakes being preferably applied to the drums, F¹ and G¹, in order that the cables, F and G, may remain under sufficient tension to avoid slack in said cables.

15 When the point for discharge has been reached, the load may be released while it is in its elevated position or the load may be lowered by holding the drum, H², releasing the drum, F¹, and turning the drum, G¹, 20 whereby the winding of the cable, G, on the drum, G¹, will draw the carriage, B, toward the carriage, C, until the load has been brought as low as is desired.

It is to be observed that the shape of the 25 carriages is such as to keep the swiveled block of the load carriage separated from the clamping device of the clamp carriage even when the carriages bear against each other. This is effected by the horizontal 30 members, B⁴, of the load carriage and the horizontal members, C⁴, of the clamp carriage. Furthermore, at such time, the load buffer, B¹⁶, on the load carriage bears against the buffer, C²⁰, of the clamp carriage and 35 the two buffers form a swivel or rocking point, whereby the load carriage is made free to swing sidewise, independently of the clamp carriage, when the free end of the load line is to be taken sidewise a short distance or several hundred feet to get a load. 40 It must be observed that in such case it is desirable to have the load carriage turn from the upright to the same inclined position as the load line takes to reach its load. And 45 in this connection it must be remembered that the two carriages are to be brought together when the load line is to be let out to approximately its maximum length.

As is already well-known in this art, the 50 drums are to be provided with friction brake or clutch mechanism allowing slipping when there is excessive strain, in order that when a limit of movement of the carriages or the load is reached, such slipping will avoid 55 damage to the mechanism.

It is to be observed that each of the cables, G and F, has both its ends secured in such manner as to avoid twisting of the cable during the operation of the apparatus, and 60 that the part of the load-line between the drum, H², and the clamp, C¹⁵, is similarly held against twisting. Thus these lines are not during operation put into such twisted condition as will cause kinking—the doubling and twisting upon each other of parts

of the cables. In the operation of similar apparatus, in which the cables are not held against twisting, serious delays and sometimes derangement and breakage of the apparatus result from such twisting. Time 70 lost and the replacing of damaged parts make large loss items.

The rollers, B¹⁸, and C²², serve to prevent the carriages from rising on the track cable, A.

I claim as my invention,

1. In an apparatus of the nature described, the combination with an elevated track and drums, of a clamp carriage supported on said track, a load carriage supported on said track between the clamp carriage and the drums, the load carriage having means for guiding the load line and having means for guiding the clamp carriage line and the clamp carriage having means for immovably clamping the load line to said carriage and having a guide roller for the clamp carriage line, a clamp carriage line having one end attached to the load carriage and extending thence horizontally to and around said guide roller of the clamp carriage and then horizontally back through the load carriage to the clamp carriage line drum, a load carriage line secured by one end to the load carriage and extending thence to the load carriage line drum, and a load line extending loosely through the guiding means on the load carriage and through the fastening means on the clamp carriage and thence away from said carriage 90 in the direction opposite the direction of the load carriage to a guide roller, and thence to other guiding means and to the load line drum, substantially as described.

2. In an apparatus of the nature described, the combination with an elevated track and drums, of a clamp carriage supported on said track, a load carriage supported on said track between the clamp carriage and the drums, the load carriage having two clevises and means for guiding the load line and having means for guiding the clamp carriage line and the clamp carriage having means for immovably clamping the load line to said carriage and having a guide 105 roller for the clamp carriage line, a clamp carriage line having one end attached to one of the clevises of the load carriage and extending thence horizontally to and around said guide roller of the clamp carriage and 110 then horizontally back through the load carriage to the clamp carriage line drum, a load carriage line secured by one end to the other clevis of the load carriage and extending thence to the load carriage line drum, and a load line extending loosely through the guiding means on the load carriage and through the fastening means on the clamp carriage and thence away from said carriage 120 in the direction opposite the direction of the 125 load line, substantially as described.

3. In an apparatus of the nature described, the combination with an elevated track and drums, of a clamp carriage supported on said track, a load carriage supported on said track between the clamp carriage and the drums, the load carriage having two clevises and means for guiding the load line and having means for guiding the clamp carriage line and the clamp carriage having means for immovably clamping the load line to said carriage and having a guide 130 roller for the clamp carriage line, a clamp carriage line having one end attached to one of the clevises of the load carriage and extending thence to the load carriage line drum, and a load line extending loosely through the guiding means on the load carriage and through the fastening means on the clamp carriage and thence away from said carriage in the direction opposite the direction of the load line, substantially as described.

load carriage to a guide roller, and thence to other guiding means and to the load line drum, substantially as described.

3. In an apparatus of the nature described, the combination with an elevated track and drums, of a clamp carriage supported on said track, a load carriage supported on said track between the clamp carriage and the drums, the load carriage having a swivel block for guiding the load line and having means for guiding the clamp carriage line and the clamp carriage having means for immovably clamping the load line to said carriage and having a guide roller for the clamp carriage line, a clamp carriage line having one end attached to the load carriage and extending thence horizontally to and around said guide roller of the clamp carriage and then horizontally back through the load carriage to the clamp carriage line drum, a load carriage line secured by one end to the load carriage and extending thence to the load carriage line drum, and a load line extending loosely through the swivel block on the load carriage and through the fastening means on the clamp carriage and thence away from said carriage in the direction opposite the direction of the load carriage to a guide roller, and thence to other guiding means and to the load line drum, substantially as described.

4. In an apparatus of the nature described, the combination with an elevated track and drums, of a clamp carriage supported on said track, a load carriage supported on said track between the clamp carriage and the drums, the load carriage having means for guiding the load line and having means for guiding the clamp carriage line and the clamp carriage having a clamping block for immovably clamping the load line to said carriage and having a guide roller for the clamp carriage line, a clamp carriage line having one end attached to the load carriage and extending thence horizontally to and around said guide roller of the clamp carriage and then horizontally back through the load carriage to the clamp carriage line drum, a load carriage line secured by one end to the load carriage and extending thence to the load carriage line drum, and a load line extending loosely through the guiding means on the load carriage and through the fastening means on the clamp carriage and thence away from said carriage in the direction opposite the direction of the load carriage to a guide roller, and thence to other guiding means and to the load line drum, substantially as described.

5. In an apparatus of the nature described, the combination with an elevated track and drums, of a first carriage and a second carriage each having in its upper part wheels resting on said track and the

first of said carriages having means for guiding the load-line and having means for guiding the first cable and the second carriage having a rocking clamping block for immovably fastening the load-line to said carriage and the second carriage having a guide roller for the first cable, a first cable having one end attached to the first carriage and extending thence horizontally to and around the guide roller of the second carriage and then horizontally back through the first carriage to a drum, a second cable secured by one end to the first carriage and extending thence in the direction opposite the direction of the first carriage and to a drum, and a load-line extending loosely through the guiding means on the first carriage and through the rocking clamping block on the second carriage and thence away from said carriage in the direction opposite the direction of the first carriage and to a drum, substantially as described.

6. In an apparatus of the nature described, the combination with an elevated track and drums, of a clamp carriage supported on said track, a load carriage supported on said track between the clamp carriage and the drums, each of said carriages comprising pairs of bars arranged to overlap and form a triangular structure, the load carriage having means for guiding the load line and having means for guiding the clamp carriage line and the clamp carriage having means for immovably clamping the load line to said carriage and having a guide roller for the clamp carriage line, a clamp carriage line having one end attached to the load carriage and extending thence horizontally to and around said guide roller of the clamp carriage and then horizontally back through the load carriage to the clamp carriage line drum, a load carriage line secured by one end to the load carriage and extending thence to the load carriage line drum, and a load line extending loosely through the guiding means on the load carriage and through the fastening means on the clamp carriage and thence away from said carriage in the direction opposite the direction of the load carriage to a guide roller, and thence to other guiding means and to the load line drum, substantially as described.

7. In an apparatus of the nature described, the combination with an elevated track and drums, of a clamp carriage supported on said track, a load carriage supported on said track between the clamp carriage and the drums, each of said carriages comprising pairs of bars arranged to overlap and form a triangular structure and the load carriage having a pair of opposed load line guiding rollers and having means for guiding the clamp carriage line and the clamp carriage having means for

- immovably clamping the load line to said carriage and having a guide roller for the clamp carriage line, a clamp carriage line having one end attached to the load carriage 5 and extending thence horizontally to and around said guide roller of the clamp carriage and then horizontally back between said pair of guiding rollers of the load carriage to the clamp carriage line drum, 10 a load carriage line secured by one end to the load carriage and extending thence to the load carriage line drum, and a load line extending loosely through the guiding means on the load carriage and through the 15 fastening means on the clamp carriage and thence away from said carriage in the direction opposite the direction of the load carriage to a guide roller, and thence to other guiding means and to the load line drum, 20 substantially as described.
8. In an apparatus of the nature described, the combination with an elevated track and drums, of a clamp carriage supported on said track, a load carriage supported on 25 said track between the clamp carriage and the drums, each carriage comprising bars arranged to over-lap and form a triangular frame and the load carriage having means for guiding the load line and having means 30 for guiding the clamp carriage line and the clamp carriage having means for immovably clamping the load line to said carriage and having intermediate its angles a guide roller for the clamp carriage line, a clamp 35 carriage line having one end attached to the load carriage and extending thence horizontally to and around said guide roller of the clamp carriage and then horizontally back through the load carriage to the clamp carriage line drum, a load carriage line secured 40 by one end to the load carriage and extending thence to the load carriage line drum, and a load line extending loosely through the guiding means on the load carriage and 45 through the fastening means on the clamp carriage and thence away from said carriage in the direction opposite the direction of the load carriage to a guide roller, and thence to other guiding means and to the 50 load line drum, substantially as described.
9. In an apparatus of the nature described, the combination with an elevated track and drums, of a first carriage and a second carriage each having in its upper part wheels 55 resting on said track and the first of said carriages having means for guiding the load-line and having means for guiding the first cable and the second carriage having a channeled rocking clamping block for immovably fastening the load-line to said carriage and the second carriage having a guide roller for the first cable, a first cable having one end attached to the first carriage and extending thence horizontally to and around 60 the guide roller of the second carriage and then horizontally back through the first carriage to a drum, a second cable secured by one end to the first carriage and extending thence in the direction opposite the direction of the first carriage and to a drum, and a load-line extending loosely through the guiding means on the first carriage and through the clamping block on the second carriage and thence away from said carriage 65 the guide roller of the second carriage and
- then horizontally back through the first carriage to a drum, a second cable secured by one end to the first carriage and extending thence in the direction opposite the direction of the first carriage and to a drum, 70 and a load-line extending loosely through the guiding means on the first carriage and through the channel of the rocking clamping block on the second carriage and thence away from said carriage in the direction opposite the direction of the first carriage and to a drum, substantially as described.
10. In an apparatus of the nature described, the combination with an elevated track and drums, of a first carriage and a second carriage each having in its upper part wheels resting on said track and the first of said carriages having means for guiding the load-line and having means for guiding the first cable and the second carriage having a clamping block for immovably fastening the load-line to said carriage said block being journaled on screw bolts extending into the sides of said block, and the second carriage having a guide roller 85 for the first cable, a first cable having one end attached to the first carriage and extending thence horizontally to and around the guide roller of the second carriage and then horizontally back through the first carriage 90 to a drum, a second cable secured by one end to the first carriage and extending thence in the direction opposite the direction of the first carriage and to a drum, and a load-line extending loosely through the 95 guiding means on the first carriage and through the clamping block on the second carriage and thence away from said carriage in the direction opposite the direction of the first carriage and to a drum, substantially as described.
11. In an apparatus of the nature described, the combination with an elevated track and drums, of a first carriage and a second carriage each having in its upper part wheels resting on said track and the first of said carriages having means for guiding the load-line and having means for guiding the first cable and the second carriage having a clamping block comprising 100 U-bolts for immovably fastening the load-line to said carriage and having a guide roller for the first cable, a first cable having one end attached to the first carriage and extending thence horizontally to and around the guide roller of the second carriage and then horizontally back through the first carriage to a drum, a second cable secured by one end to the first carriage and extending thence in the direction opposite the direction of the first carriage and to a drum, and a load-line extending loosely through the 105 guiding means on the first carriage and through the clamping block on the second carriage and thence away from said carriage in the direction opposite the direction of the first carriage and to a drum, substantially as described.
12. In an apparatus of the nature described, the combination with an elevated track and drums, of a first carriage and a second carriage each having in its upper part wheels resting on said track and the first of said carriages having means for guiding the load-line and having means for guiding the first cable and the second carriage having a clamping block comprising 110 U-bolts for immovably fastening the load-line to said carriage and having a guide roller for the first cable, a first cable having one end attached to the first carriage and extending thence horizontally to and around the guide roller of the second carriage and then horizontally back through the first carriage to a drum, a second cable secured by one end to the first carriage and extending thence in the direction opposite the direction of the first carriage and to a drum, and a load-line extending loosely through the 115 guiding means on the first carriage and through the clamping block on the second carriage and thence away from said carriage in the direction opposite the direction of the first carriage and to a drum, substantially as described.
13. In an apparatus of the nature described, the combination with an elevated track and drums, of a first carriage and a second carriage each having in its upper part wheels resting on said track and the first of said carriages having means for guiding the load-line and having means for guiding the first cable and the second carriage having a clamping block comprising 120 U-bolts for immovably fastening the load-line to said carriage and having a guide roller for the first cable, a first cable having one end attached to the first carriage and extending thence horizontally to and around the guide roller of the second carriage and then horizontally back through the first carriage to a drum, a second cable secured by one end to the first carriage and extending thence in the direction opposite the direction of the first carriage and to a drum, and a load-line extending loosely through the 125 guiding means on the first carriage and through the clamping block on the second carriage and thence away from said carriage in the direction opposite the direction of the first carriage and to a drum, substantially as described.

riage in the direction opposite the direction of the first carriage and to a drum, substantially as described.

12. In an apparatus of the nature described, the combination with an elevated track and drums, of a clamp carriage and a load carriage supported on said track, said carriages being movable lengthwise on the track independently of each other and the upper parts of said carriages being so formed that said parts may abut against each other while other parts of the carriages are free from each other, whereby, while said carriages bear against each other, the load carriage is free to swing sidewise independently of the clamp carriage, and said carriages being adapted for engagement with the below-mentioned lines, and a clamp carriage line and a load carriage line and a load line associated with said carriages and said drums, substantially as described.
13. In an apparatus of the nature described, the combination with an elevated track and drums, of a clamp carriage supported on said track, a load carriage supported on said track between the clamp carriage and the drums, said carriages being movable lengthwise on the track independ-

ently of each other and the upper parts of said carriages being so formed that said parts may abut against each other while other parts of the carriages are free from each other, whereby, while said carriages bear against each other, the load carriage is free to swing sidewise independently of the clamp carriage, and said carriages being adapted for engagement with the below-mentioned lines, and a clamp carriage line and a load carriage line and a load line associated with said carriages and said drums, substantially as described.

14. In an apparatus of the nature described, the combination with an elevated track and drums, of a clamp carriage and a load carriage supported on said track and each of said carriages comprising pairs of bars arranged to over-lap and form a triangular structure, bumpers on the ends of the horizontal bars, and a load line and a clamp carriage line and a load carriage line associated with said carriages and drums, substantially as described.

In testimony whereof I have signed my name, this 5th day of December, in the year one thousand nine hundred and nineteen.

RICHARD L. NEUBERT.
